CABINET

Roy Ruch, Sunbury, Pa.

Application March 10, 1948, Serial No. 14,070

1 Claim. (Cl. 312—351)

1

This invention relates to cabinets and has particular reference to a cabinet which is so constructed and arranged that all parts of the interior thereof are fully illuminated when the door is opened to thereby facilitate the emplacement of articles in the cabinet and the removal of the same therefrom.

The invention has in view a cabinet such as a refrigerator and the like having shelves and interior panelling which permits of the passage of light rays therethrough and which are so arranged that an electric light positioned between the wall of the cabinet and the interior panelling illuminates all parts of the interior thereof.

Still another object of the invention is the provision of a cabinet having transparent shelves and translucent interior panelling which latter diffuse the light rays while the transparent shelves permit of the free passage of the diffused light therethrough.

Still another object of the invention is the provision of a cabinet of said character in which switch means is provided for automatically connecting the illuminating means with a source of current when the door is opened and for breaking the connection when the door is closed.

A further object of the invention is the provision of means for securing the shelves and interior panelling in position within the cabinet.

With the foregoing and other objects in view, reference is now made to the following specification and accompanying drawings in which the preferred embodiment of the invention is illustrated.

In the drawings:

Fig. 1 is a view in front elevation of a cabinet constructed in accordance with the invention.

Fig. 2 is a horizontal sectional view taken approximately on line 2—2 of Fig. 1.

Fig. 3 is a vertical sectional view taken approximately on line 3—3 of Fig. 2.

Fig. 4 is a fragmentary perspective view illustrating the construction for supporting the shelves and interior panelling.

Referring to the drawings by characters of reference, the cabinet may be employed for the storage of any desired type of article and for such purpose the walls of the cabinet may be made of any suitable material.

As illustrated, the cabinet consists of a rear wall 10, opposite side walls 11 and 12, top and bottom walls 13 and 14 and a front wall frame 15 defining a rectangular opening 16 for the placement of articles in the cabinet and the removal of the same therefrom and which opening is adapted

5 to be closed by a hinged door or closure 17. If desired, the cabinet may be formed with a drawer 18 slidably arranged in the lower portion thereof and having a front wall 19. The front wall 19 is provided with a handle 20 for facilitating the sliding of the drawer into position within the closet and the removing of the same therefrom for depositing articles therein while the door 17 is provided with a handle 21 having a latch element 22 for securing the door in closed relation.

10 In order to illuminate all parts of the interior of the cabinet so as to facilitate the placement of articles therein or the removal of the same therefrom, the cabinet is provided with vertical panels

15 23 fashioned of translucent material such as frosted glass and the like and which are arranged within the cabinet in laterally spaced relation from the side walls 11 and 12 to thereby

20 provide a space between the panels and the adjacent side walls respectively for accommodating an electric light bulb indicated by the reference character 24. The cabinet is also provided with one or more shelves 25, two being shown in the

25 present embodiment which are fashioned of transparent material such as clear glass and the like and which extend from the front of the cabinet to the rear thereof and between the vertical panels 23. A shelf or wall 26 may also be provided which

30 is disposed above the drawer 18 and forms the top wall thereof. The shelf or wall 26 is similarly fashioned of transparent material such as clear glass so that the interior shelves and panels within the cabinet will permit of the passage of light

35 rays therethrough in order that illumination from the bulbs 24 will extend to all parts of the interior of the cabinet as well as to the drawer 18. The vertical panels 23 being of translucent material diffuse the light throughout the whole surface thereof so as to prevent glare of the light within the cabinet while the panels also separate the bulbs 24 from the articles stored in the cabinet.

40 The panels 23 and the shelves 25 may be supported in the cabinet in any desired manner such as by brackets 27 which are formed with an inwardly extending forward end 28 provided with a vertical slot 29. The brackets 27 are secured by studs 30 to the inner face of the rear wall 10 and the front frame 15 adjacent each of

45 the side walls 11 and 12 for receiving the vertical edge portions of the vertical panels 23 in the slots 29, while the shelves 25 are supported on the upper edge portions 31 thereof. The vertical panels 23 are supported at their lower ends 50 upon the shelf or wall 26 which is secured at

its opposite side edges in notches 32 in the side walls 11 and 12 of the cabinet.

The cabinet is provided with a switch button 33 protruding through the wall defining the door opening 16 for engagement by the rear side edge of the door 17. The switch button 33 is connected with the bulbs 24 by conductor wires (not shown) for connecting the bulbs in an electric circuit so as to illuminate the cabinet when the door is opened and for breaking the circuit when the door is closed.

What is claimed is:

A cabinet having a rear wall, opposite side walls, top and bottom walls and a front wall having an opening, said side walls having grooves in the inner faces thereof respectively arranged in oppositely disposed relation and located in spaced relation from the bottom wall of the cabinet, a transparent horizontally disposed partition secured at its ends in said grooves to divide the interior of said cabinet into upper and lower compartments, vertical panels of translucent material arranged in said upper compartment and supported on said partition in laterally spaced relation from said side walls respectively to thereby provide a space between said side walls and said panels respectively, upper and

lower brackets secured to said front and rear walls and engaging over the edges of said vertical panels for securing the same in upright relation, and a transparent shelf arranged between said vertical panels and supported on said upper brackets.

ROY RUCH.
